UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

LOOM-STOPPING MECHANISM.

Application filed July 26, 1927. Serial No. 208,495.

This invention relates to loom stopping mechanism and is more particularly directed to means for effecting loom stoppage on the occurrence of a warp fault.

5 It is now the ordinary practice to provide looms with means for stopping the loom upon the occurrence of a warp fault, such as a broken or too slack warp thread, in order that the loom attendant may correct the fault and
 10 piece up the broken end or take up the undue slack. In looms of the above general character it is customary for the loom attendant to turn the loom over by hand after it has been brought to rest, to thereby position the warp
 15 threads so that the broken or slack end may be corrected. In turning the loom over by hand, the loom attendant must not only take note by his eye of the position of the warp threads, but must also give attention to the
 20 position of the shuttle and see that the shuttle is in the proper box when he has turned the loom over. This frequently necessitates movement of the shuttle in the shed by hand and much time is wasted in thus positioning
 25 the warp threads and the shuttle after the loom has been stopped so that the attendant may correct the warp fault.

One of the objects of the present invention is to provide loom stopping means which will
 30 act upon the occurrence of a warp fault to stop the loom with the shuttle always in the same box, preferably at the shipper side of the loom, and with the shed closed or substantially closed, thereby relieving the loom attendant of any necessity of turning the loom over by hand to properly position the parts and the warp threads for piecing up.

In accordance with the present invention, the warp stopping mechanism is of the transversely movable toothed bar type in which the toothed detector bar is given its detecting movement on every other beat-up movement of the lay or every other pick of the shuttle, and means are under control of the warp stop mechanism to throw off the power from the loom by frontward movement of the lay when the shuttle is absent from the box at the shipper side of the loom, so that the momentum of the loom may carry the lay to its full back position to cause the return of the shuttle to the box at the shipper side of the loom and come to rest with the lay between front and back position, with the shuttle in

the box at the shipper side of the loom and the shed closed or substantially closed, which 55 is the most advantageous position of the warp threads for "piecing up".

The invention and new combination of parts will best be made clear from the following description and the accompanying 60 drawings of one good form thereof.

In the drawings:

Fig. 1 is a perspective view of portions of a loom at the shipper side thereof and provided with the present invention; 65

Fig. 2 is a side sectional elevation on a somewhat enlarged scale showing the relation of parts when the warp stop mechanism has detected a fault in the warp threads and positioned the dog for operation by frontward 70 movement of the lay;

Fig. 3 is an enlarged elevation showing a portion of a transversely movable toothed detector bar warp stop mechanism; and

Fig. 4 is a detached detail in side elevation 75 showing a loom provided with the present invention.

The loom frame 1 may be of usual construction, and mounted in suitable bearings at each side of the loom frame is the crank shaft 80 2 connected by the crank 3 to the pitman 4 connected at 5 to the lay 6, whereby the lay is given its usual movements.

Mounted on the crank shaft is the gear 7 which meshes with the gear 8 mounted on the 85 cam shaft 9 below the crank shaft, the size of the gears 7 and 8 being such as to impart to the cam shaft one revolution to each two revolutions of the crank shaft.

Mounted on the crank shaft 2 are the fast 90 and loose pulleys 10 and 11 and a brake drum 12. The crank shaft 2 is given its rotary movements by means of a belt 13, Fig. 1, which passes through the loop of a belt shifter 14 whereby the belt may be shifted from 95 one pulley to the other.

Mounted on the loom frame is the bridge member 15 which may afford a convenient support for one end bearing of the crank shaft 2, and such bridge member is connected to the loom frame by the bars 16 and 17. Mounted on the bar 17, Fig. 1, is the front end portion 18 of the belt shifter from which extends a pin 19 engaged with a slot 20 on the shifting arm 21 which may be pivoted at 105 22 to a bracket 23 secured to the loom frame.

The frontwardly extending end portion 24 of the belt shifter is engaged with the lower end portion 25 of the shipper lever 26 pivotally mounted at 27 to the bracket 28 extending from the loom frame. The upper end of the shipper 26 is provided with the usual handle 29 and when the loom is in operation the shipper 26 is retained within the notch 30 formed on the shipper stand, as usual, the construction being such that should the shipper be released from its notch 30, as will hereinafter be explained, the belt 13 will be transferred from the fast to the loose pulley, as indicated in Fig. 1.

15 Mounted on the stud 31 extending from the loom frame is the hub portion of the brake arm 32 having an upwardly extending toe 33 which is adapted to act through the block 34, Fig. 1, and the rod 35 to apply the brake 36 to the brake drum 12. The shipper lever 26 is provided with a lifting toe 39 which underlies the frontwardly extending portion of the brake arm 32, the construction being such that when the shipper is in running position 25 the brake arm 32 will be lifted to relieve the brake. Secured to the brake lever is the spring 40, Fig. 1, which, when the shipper lever is detached from its holding notch, acts upon the brake arm 32 to apply the brake to 30 the brake drum to thereby overcome the momentum of the loom when the shipper lever has shipped or transferred the belt from the fast to the loose pulley, as will be more fully explained.

35 The warp stop mechanism, as hereinbefore stated, is of the transversely movable toothed bar type wherein movable and fixed toothed bars have relative transverse movement during loom operation and the movable toothed bar is brought to rest by a drop wire 41 when a warp fault occurs. In the present instance of the invention, the fixed toothed bar 42 is secured at its ends to a bracket 43, one at each side of the loom. The movable toothed 40 detecting bar 44 is connected by a link 45 to a bar actuator 46, the lower end portion of which has pins or fulcra 47 which rest in seats in the rocker 48, and a spring 49 normally holds the toothed bar actuator in its normal 45 position, as indicated in Fig. 3. The parts of the warp stop mechanism so far described may be substantially as shown and described in the Davis and Johnson Patent, No. 1,538,- 625, dated May 19, 1925.

50 Pivots mounted on the rocker 48 at 50 is the stop finger 51 which normally bears upon a lever 52 pivotally mounted at 53 on the rocker 48, and the inner end portion of the stop finger 51 has a pin 54 which enters a slot 55 in the bar actuator, the construction being such that should the bar actuator be arrested 55 in its movement by a drop wire, the inner end of the stop finger will be lifted to depress the lever 52 to effect loom stoppage.

55 The rocker 48 is connected with the shaft

56 which is itself connected to an arm 57 actuated from the lower or cam shaft 9 through the link connections 58 and 59.

As hereinbefore stated, the transversely movable detector bar is given its detecting movements once on each two beat-up movements of the lay or each alternate pick of the shuttle, and as a convenient means to this end the link 59 is provided with a yoke 60, the bifurcated end of which straddles the lower or cam shaft 9 to guide the link 59 in its up and down movements. Mounted on the lower or cam shaft 9 is the link actuator which comprises two cams 61 and 62 each of which has a groove, preferably formed as face cams, 80 to engage a switch 63 pivotally mounted on the yoke 60 at 64. The cam 61 which in the present instance of the invention is the cam for lifting the link 59, has a switch controlling portion 65 for throwing the switch 63 85 so that it will engage first one cam and then the other, the cam 62 being the cam for drawing down the link 59.

90 Each of the cams 61 and 62 has a dwell portion *a* and *b*, as represented by the arrows, Fig. 2, and after the active portion of either cam has moved the transversely movable detecting bar, such bar will dwell for substantially a half revolution of the lower or cam shaft, and since the lower or cam shaft makes one revolution to each two revolutions of the crank shaft, it follows that a detecting movement of the detector bar will occur in one or the other direction on alternate movements 95 of the lay, or, in other words, on alternate revolutions of the crank shaft.

100 The warp stop mechanism, as hereinbefore described, Fig. 3, is connected by a train of mechanism to a dog at the front of the loom, which is mounted on the shipper knock-off, so that upon the occurrence of a warp fault, the dog will be placed in the path of a bunter mounted on the lay to cause the shipper to be knocked off as the lay moves frontward, whereupon the belt shifter transfers the belt 110 from the fast to the loose pulley and the brake is simultaneously applied to effect final stoppage of the lay after it has knocked off the shipper, gone to its back position to permit the shuttle to be picked to the box at the shipper side of the loom, and has finally stopped 115 when it is in about one-third front position. This is the most convenient position for the loom attendant to piece up broken ends, because the shed is then closed or substantially closed and the shuttle is in the box at the shipper side of the loom.

120 Pivots mounted on a pin 66 is the shipper knock-off 67 the end 68 of which bears against the front of the shipper lever 25. Pivots connected to the shipper knock-off 67 at 69 is the rearwardly extending dog 70 which rests upon a plunger or pin 71 carried by a casing 72 mounted on the lower extended portion 73 of the shipper knock-off. The 125

plunger 71 is connected by a flexible sheathed wire 74 to a corresponding plunger or pin 75 normally resting against the end of the lever 52 of the warp stop mechanism, Fig. 3, under the influence of a spring 76. The construction is such that should the transversely movable detector bar on one of its movements during alternate beat-ups of the lay be arrested by a drop wire, the sheathed wire 74 will be moved 10 endwise in the sheath to lift the dog from its dotted to its full line position, Fig. 2, so that as the lay moves forwardly, the bunter 77 which is mounted upon the lay will strike the dog and knock off the shipper as the lay moves 15 forwardly. As the shipper is thus knocked off, the belt will be shifted from the fast to the loose pulley and the brake will simultaneously be applied to arrest the lay only after it has gone to its full back position to enable 20 the shuttle to be picked into the box at the shipper side of the loom and finally bring the loom to rest with the lay in about one-third front position.

Since the dog 70 and the sheathed wire actuating plunger 71 are mounted upon the downwardly extended portion of the shipper knock-off, they will retain their normal relation even when the shipper knock-off is actuated to throw the power from the loom as the 30 lay moves forwardly.

It may sometimes be desirable to guide the movement of the belt shifter, and under such circumstances the side portion 18 of the belt shifter may be provided with an arm 78, Fig. 35 1, the end of which may move in the guide 79 secured to the loom frame.

From the construction described it will be apparent that the transversely movable toothed detecting bar is given a detecting 40 movement on each alternate beat-up movement of the lay and should the movement of the detecting bar be arrested by a drop wire as the lay moves forwardly, the dog 70 which is under the control of the warp stop mechanism, will be raised into the path of the bunter 77 secured to the lay and through the shipper knock-off act to disconnect the loom from the power actuating means, and under the momentum of the loom parts the lay will 45 make its full back movement, so that the shuttle which was absent from the box at the shipper side of the loom when the power was removed therefrom, will be returned to the box at the shipper side of the loom and 50 the brake will act to stop the loom with the lay between its back and front position, with the shuttle in the box at the shipper side of the loom and the shed closed or partially closed, which is the most convenient position 55 of the warp threads for piecing up by the loom attendant. When the loom is set up ready to start weaving care should be taken to see that the shuttle is placed in the proper box, whereupon the loom will always be 60 stopped with the shuttle in the same box and 65

the shed closed or substantially closed. This will relieve the loom attendant of the duty of turning the loom over by hand, so that such attendant can run more looms than heretofore with resultant greater production in 70 cloth.

Should it be desirable at any time to turn the loom over by hand for any reason after it has been stopped, this can easily be done by means of the hand-piece 80, Fig. 1, which has connected therewith the finger 81 connected to the upper end 82 of a reach rod 37 which passes through an opening 38 in the brake arm 32. But owing to the fact that the loom is always stopped as hereinbefore described, such hand manipulation of the loom is seldom required.

What is claimed is:

1. In a loom, the combination of the lay and shuttle boxes, a warp stop mechanism having a transversely movable toothed detecting bar constructed so that its movement in either direction will effect loom stoppage upon detecting a displaced drop wire, means for imparting a transverse detecting movement to the 90 bar only on alternate beat-up movements of the lay, a series of drop wires normally supported by the warp threads during weaving, a shipper knock-off dog at the front of the loom under control of the warp stop mechanism, a bunter carried by the lay to engage the dog on the occurrence of a warp fault upon an alternate forward movement of the lay that the loom may be brought to rest with the shuttle always in the same box.

2. In a loom, the combination of the lay and shuttle boxes, a warp stop mechanism having a transversely movable toothed detecting bar, means for imparting a detecting movement to the toothed bar in either direction only on alternate picks of the shuttle, a shipper, a shipper knock-off dog at the front of the loom, a bunter on the lay for operating the dog on forward movement of the lay to knock off the shipper, connections between the warp stop mechanism and knock-off dog for positioning the dog for engagement by the bunter upon the occurrence of a warp fault on one of the alternate picks of the shuttle, and means for bringing the loom to rest with the lay between its back and front positions and the shuttle always in the same shuttle box.

3. In a loom, the combination of the lay and shuttle boxes, a warp stop mechanism having a transversely movable toothed detecting bar, means for imparting a transverse detecting movement to the detecting bar in either direction only on each alternate pick of the shuttle, a shipper, a shipper knock-off dog at the front of the loom under control of the warp stop mechanism, a bunter on the lay for operating the dog on forward movement of the lay to knock-off the shipper when the shuttle is absent from the box at the 130

shipper side of the loom, and means for bringing the loom to rest when the shuttle is returned to the shuttle box at the shipper side of the loom and the lay has gone back and then advanced a part stroke.

4. In a loom, the combination of the lay and shuttle boxes, a driving belt and fast and loose pulleys for controlling the loom operation, a belt shifter, a warp stop mechanism including drop wires and a transversely movable detector, means for imparting a detecting movement to the detector in either of its traverse movements only on alternate picks of the shuttle, a shipper for transferring the belt from one pulley to the other, a shipper knock-off dog at the front of the loom under control of the warp stop mechanism, a bunter on the lay acting through the dog on forward movement of the lay to knock off the shipper and transfer the belt from the fast to the loose pulley, and means operative to bring the loom to rest after the knock-off and the lay has gone back and been advanced to shed closed position with the shuttle always in the same box at the shipper side of the loom after the shipper has been knocked off.

5. In a loom, the combination of the lay and shuttle boxes, a warp stop mechanism having drop wires and a transversely movable toothed detector bar, means for imparting transverse detecting movement to said bar in either direction only on every other pick of the shuttle, a shipper, means controlled by the warp stop mechanism for knocking off the shipper by forward movement of the lay when the shuttle is absent from the box at the shipper side of the loom, and means for bringing the loom to rest with the shed closed when the shuttle has been returned to the shuttle box at the shipper side of the loom that the loom by momentum of the loom may be stopped by the warp stop mechanism with the shuttle always in the box at the shipper side of the loom.

6. In a loom, the combination of the lay and shuttle boxes, a warp stop mechanism having drop wires and a transversely movable toothed detector bar, means including a switch cam for imparting a detecting movement to the detector bar only once during two picks of the shuttle, a shipper, a shipper knock-off dog at the front of the loom operatively positioned by detection of a warp fault, a bunter on the lay acting on the operatively positioned dog as the lay moves forwardly to knock off the shipper and free the loom from power operation, and means for bringing the loom to rest only after the momentum of the loom has caused the shuttle to be returned to the shuttle box at the shipper side of the loom.

7. In a loom, the combination of the lay and shuttle boxes, a warp stop mechanism having drop wires, a transversely movable toothed detector bar, means for imparting a

transverse detecting movement to said bar only on every other pick of the shuttle, a shipper, a knock-off lever, a dog pivotally mounted on the knock-off lever, a bunter on the lay, means controlled by detection of a warp fault for positioning the dog to be struck by the bunter on forward movement of the lay to knock off the shipper and free the loom from power operation, and means acting after the loom has been freed from power operation for bringing the loom to rest only after the loom momentum has carried the lay to its back position and then forward to an intermediate position and the shuttle has been picked that the shuttle may always be in the box at the shipper side of the loom when the loom is stopped and the shed be substantially closed.

8. In a loom, the combination of the lay and shuttle boxes, a warp stop mechanism having drop wires and a transversely movable toothed detector bar, means for imparting transverse detecting movement to the bar only on every other pick of the shuttle, a shipper, a knock-off lever, a dog pivotally connected to the knock-off lever, a bunter on the lay, means controlled by detection of a warp fault for positioning the dog for engagement by the bunter on forward movement of the lay only when the shuttle is absent from the box at the shipper side of the loom, and means operable to stop the loom only after its momentum has carried the lay to its back position and forward to an intermediate position and shuttle has been picked that the shuttle may be returned to the box at the shipper side of the loom when the loom is finally stopped.

9. In a loom, the combination of the lay and shuttle boxes, a driving belt and fast and loose pulleys for controlling the loom operation, a belt shifter, warp stop mechanism including drop wires and a transversely movable toothed detector bar, means for imparting a transverse detecting movement to the bar only on alternate picks of the shuttle, a shipper for transferring the belt from one pulley to the other, a shipper knock-off, a dog pivotally connected to the shipper knock-off and operatively positioned on the occurrence of a warp fault when the shuttle is absent from the box at the shipper side of the loom, a bunter on the lay acting through the dog on forward movement of the lay to knock off the shipper and transfer the belt from the fast to the loose pulley, and means operable to stop the loom only after its momentum has carried the lay to its back position and forward thereof and the shuttle picked that the shuttle may always be in the box at the shipper side of the loom when the loom is stopped.

10. In a loom, the combination of the lay and shuttle boxes, a warp stop mechanism having a transversely movable toothed de-

tector bar, means for shifting the toothed bar back and forth and for holding the bar at each end of its stroke during one beat-up so that the bar is shifted only on alternate beat-up movements of the lay, a series of drop wires normally supported by the warp threads during weaving, a shipper knock-off at the front of the loom under the control of the warp stop mechanism, means carried by

the lay to engage and shift the shipper knock-off on the occurrence of a warp fault upon an alternate forward movement of the lay that the loom may be brought to rest with the shuttle always in the same box. 10

In testimony whereof, I have signed my name to this specification.

HARRY A. DAVIS.
